UNITED STATES PATENT OFFICE.

WILLIAM HORN AND JAMES HAGAN, OF ONEONTA, NEW YORK, ASSIGNEES TO
QUALITY SILK MILLS, INC., OF NEW YORK, N. Y., A CORPORATION OF NEW
YORK.

GLOVE-POINTING MACHINE.

1,378,820.

Specification of Letters Patent. Patented May 17, 1921.

Application filed September 22, 1920. Serial No. 412,051.

To all whom it may concern:

Be it known that we, WILLIAM HORN and JAMES HAGAN, both citizens of the United States, and both residents of the city of Oneonta, county of Otsego, and State of New York, have jointly invented certain new and useful Improvements in Glove-Pointing Machines, of which the following is a specification, reference being had to the accompanying drawings.

According to the present mode it is customary to ornament or finish the points upon the backs of gloves with what are known in the trade as spearhead terminals.

To properly form such terminals, so that the wings and so-called tail thereof shall be of proper length and at a proper angle relative to the body of the point requires a high degree of skill on the part of the operator of the pointing machine, and irrespective of the skill of the operator the time required to properly produce the spearheads is such as to materially increase the cost of manufacture. It is the purpose of this invention, therefore, to provide the presser foot of the machine with certain pointers and observation openings so located and arranged that the operator using them as guides may quickly and with accuracy produce the spearheads.

Referring to the drawings, Figures 1 to 6 are plan views of the back of a short-wristed glove blank illustrating the respective positions and movements of the blank to successively produce the various parts of the spearhead; Fig. 7 is an edgewise elevation and Fig. 8 is a front elevation of the presser foot of a glove pointing machine embodying our invention.

In the drawings the points are shown as having been made by a three needle machine and the spearheads as produced by a two needle machine. Obviously such number of needles as may be preferred may be used for the production of the points and spearheads.

Referring first to Figs. 7 and 8, 1 represents the presser foot, which, except as hereinafter described, may be made of any preferred material and in any preferred form adapted to use upon any preferred machine. Its needle plate is provided with a series of pointers as hereinafter described, those illustrated being one form only of many which may embody our invention. As illus-

trated, 2 represents a pointer projecting laterally from the needle plate, 3 another pointer projecting forwardly from the central part of the front edge of the needle plate and 4 another pointer at the front edge of the side of the needle plate opposite that from which the pointer 2 projects. In the form shown the pointer 4 is merely the forward rectangular corner of the needle plate, but obviously any equivalent construction may be substituted therefor. 5, seen best Fig. 1, is the needle opening, two needles being illustrated therein. 6 is an observation opening having, preferably, a crossbar 7 bisecting the same.

The operation is as follows: Assume that the spearhead is to be formed on the right hand point 8, the spearheads upon the other two points having already been made. The presser foot being elevated the operator places the glove blank upon the table of the machine in such manner that the end of the pointer 2 registers with the center of the point 8, the end of the point being visible through the observation opening 6 directly beneath the crossbar 7. Thereupon the presser foot is dropped, the machine is started, with the blank moving in the direction of the arrow under the influence of the feed, see Fig. 1, whereupon the left hand wing 9, shown in dotted lines in Fig. 2, will be produced. The presser foot being then elevated the blank is swung to the left into the position shown in Fig. 2 until the pointer 3 registers with the center of the body of the point, the needles being at the end of the point. Thereupon the presser foot is dropped, and the machine started, with the blank being fed in the direction of the arrow shown in Fig. 2, the stitching being continued until the pointer 3 arrives at the junction between the wing 9 and the end of the point, thus producing the tail 10 of the spearhead, the needles being at the forward end of the tail, all as shown in Fig. 3. Thereupon the feed is reversed, as indicated by the arrow in Fig. 3, and the needles are brought back along the line of the tail to the position shown in Fig. 4. Thereupon the blank is swung to the left, as indicated by the arrow in Fig. 4, until the pointer 4 registers with the center of the point 8, the needles being at the junction between the wing 9, tail 10 and end of the point 8. Thereupon

100

105

the presser foot is again dropped, the machine started, the blank moving under the action of the feed in the direction of the arrow as shown in Fig. 5, and the stitching continued until the needles travel from the position shown in Fig. 5 until the crossbar 7 of the observation opening 6 registers with the junction between the wing 9, tail 10 and end of the point 8 as shown in Fig. 6, thereby producing the right hand wing 11 of the point, thus finishing the spearhead. The threads are then cut and the blank removed from the machine as usual.

It will be noted that by reason of the pointers or guides supplied under our invention upon the needle plate of the presser foot of the machine, the operator is afforded means whereby he may quickly and easily determine the proper position of the blank relative to the needles of the machine and may without delay or undue care or observation proceed with the stitching, having assurance that the various elements of the spearhead will all be accurate and in proper position relative to each other and to the body of the point.

It will be obvious to those who are familiar with this art that the special form of the various pointers and their location relative to the needle plate and needle opening therein may be altered to suit the requirements of the special work in hand and the special form of spearhead or other ornamentation and that other modifications may be made in the details of construction, all without departing from the essentials of our invention. We therefore do not limit ourselves to the details shown and described.

We claim:

1. A presser foot for a glove pointing machine having a pointer projecting laterally from its needle plate, another pointer projecting forwardly from the central part of the front edge of its needle plate and another pointer at the front edge of the side of the needle plate opposite that from which the lateral pointer projects.

2. A presser foot for a glove pointing machine having a pointer projecting laterally from its needle plate, another pointer projecting forwardly from the central part of the front edge of its needle plate, another pointer at the front edge of the side of the needle plate opposite that from which the lateral pointer projects and an observation opening in the needle plate in rear of the needle opening therein.

3. A presser foot for a glove pointing machine having a pointer projecting laterally from its needle plate, another pointer projecting forwardly from the central part of the front edge of its needle plate, another pointer at the front edge of the side of the needle plate opposite that from which the lateral pointer projects, an observation opening in the needle plate in rear of the needle opening therein, and a bisecting crossbar in the observation opening.

4. A presser foot for a sewing machine having an observation opening in rear of the needle opening and a crossbar bisecting the said observation opening.

In testimony whereof we have signed our names to this specification.

WILLIAM HORN.
JAMES HAGAN.
